UNITED STATES PATENT OFFICE.

GEORGE J. FOX AND ADAM FOERSTER, OF LANSING, MICHIGAN.

FAUCET-SOCKET.

SPECIFICATION forming part of Letters Patent No. 391,891, dated October 30, 1888.

Application filed June 6, 1887. Serial No. 240,494. (No model.)

To all whom it may concern:

Be it known that we, GEORGE J. FOX and ADAM FOERSTER, citizens of the United States, residing in the city of Lansing, Ingham county, Michigan, have invented a new and useful 5 Faucet-Socket, of which the following is a specification.

This invention relates to certain new and useful improvements in bushings for faucets for 10 kegs, barrels, hogsheads, and the like of that class in which two or more parts are employed; and the novelty in the present instance resides in the peculiarities of construction and the 15 combinations, arrangement, and adaptation of parts, all as more fully hereinafter described and claimed.

The invention is clearly illustrated in the accompanying drawings, in which—

Figure 1 is a perspective view of the thimble 20 of our improved bushing. Fig. 2 is a like view of the wooden plug. Fig. 3 is a similar view of the nut. Fig. 4 is a top plan of the device complete, and Fig. 5 is a cross-section of the same screwed into a barrel side.

Referring to the details of the drawings by letter, A designates a portion of the side of a barrel, into which is screwed the thimble or bushing B, formed at its inner end with an interior annular flange, a, and at the other end 30 with an annular shoulder, b, to limit the movement of the thimble into the barrel side. This thimble is preferably of metal, and is provided upon its interior, as well as upon its exterior, with screw-threads, as shown. C is a wooden hollow plug, the inner end of which is designed to rest upon the flange a of the thimble B, and formed substantially near the center of its length with an annular shoulder, c, leaving the outer portion of the plug

of less diameter, as shown. D is an exteriorly-threaded nut fitting between the reduced portion of the plug and engaging the interior threads of the thimble B, as seen in Fig. 5. This nut is formed at its outer end with an inwardly-extended flange, e, bearing on the 45 shoulder c of the plug C.

Both the thimble B and nut D may be provided with holes d, if desired, for the reception of a suitable instrument by which they may be turned.

Importance is attached to the reduced portion of the wooden plug in connection with the inwardly-extended flange of the nut, for by this construction the plug can always be kept hard up against the flange a of the bushing, thus guarding against leakage, and at the same time the whole aperture through the socket is lined by the wooden plug. The wooden plug is of less diameter than the aperture in the nut, to provide room for swelling of 60 the plug.

What we claim is—

The combination, with the thimble having interior shoulder or flange, a, of the wooden plug C, resting at one end on said flange and 65 at its other formed with reduced portion and shoulder c, and the nut D, inserted between the bushing and nut, screw-threaded to engage the internal threads of the bushing, and formed with inwardly-extended flange e, engaging the shoulder c of the wooden plug, substantially as 70 shown and described.

GEORGE J. FOX.
ADAM FOERSTER.
